SAFETY SKI HARNESS

Karl W. Gruppe, Utica, N. Y.

Application July 12, 1940, Serial No. 345,044

10 Claims. (Cl. 280—11.35)

My present invention relates to a safety ski harness.

The purpose of this invention is to provide a safety ski harness of new and improved construction and one which is economical in original construction and in being applied to skis, and which is efficient and reliable in operation and not liable to get out of order.

It is well known among skiers that an accidental forward fall by a skier is a fall that is most likely of all accidents to seriously injure the skier and particularly to cause a fracture or breakage of the ankle joint or of the bone of the leg near the ankle joint.

As far as I am informed none of the present forms of ski harness allows for a sufficiently quick release of the foot of the skier from the ski when the person using the skis falls forward. The main purpose of this invention is to provide a ski harness which automatically unlocks from the harness the user's foot and shoe when the skier accidentally falls forward.

A further purpose is to provide a safety ski harness of the type mentioned which will positively unlock the latch holding the harness to the skier's shoe on the sharp raising of the heel and the front of the ankle of the skier's shoe, which occurs when he falls forward, and which safety ski harness nevertheless will not operate to release the shoe unless the forward part of the ankle portion of the shoe is brought upwardly into actual engagement with a part of the bridge portion of the safety harness. In other words my invention is to be definitely distinguished from those so-called safety devices which detach the shoe of the skier from the ski harness simply on a sharp increase in sidewise or twisting tension imparted to some part of the ski harness.

A further purpose of this invention is also to provide a releasable bridge over the foot and connecting the two sidewalls of the harness with one of the sidewalls positively located and the other one hingedly mounted at its lower end and normally held in place by the hooked or latched engagement of a bridge member connecting the upper ends of the said sidewalls or plates of the harness.

A further purpose is to provide in combination with such a construction a detachable device which normally holds one end of the cable which passes around the grooved rear end of the heel of the skier's shoe, with said device so constructed that on the swinging open of the hinged side of the harness the said holding device will also

release the end of the said cable and to that further extent cause a complete and instantaneous release of the shoe from the ski.

Further purposes and advantages of the invention will appear from the specification and claims herein.

Fig. 1 is an isometric view of the relevant portion of a ski harness embodying the different features of this invention, said safety ski harness showing the ski harness adapted for holding the right shoe, the parts of the harness being shown in their connected and operative positions. The front of the ski is cut off directly in front of the body of the harness and also to the rear of the harness.

Fig. 2 is a transverse sectional view of the parts shown immediately on line 2—2 of Fig. 1.

Fig. 3 is an outer or right side elevation of the harness shown in Fig. 1 and in the position of the parts shown in that view, said view also showing the means for normally holding the short front end of the heel cable.

Fig. 4 is a detailed side elevation of the upper part of the harness shown in Fig. 3 but with the outer or right hand end of the overhanging bridge piece shown at the instant it has swung upwardly at its rear side and before the swingingly or hingedly mounted outer or right plate has sprung outwardly, and before the front hook on the forward right corner of the said bridge piece has become disengaged from the projection upon the adjacent upper front corner of this swinging side wall or plate.

Fig. 5 is a detail view showing the top edge of the hinged side plate 11, and particularly showing the outwardly turned slanting portion 24 and the still further outwardly turned forward upper corner 27 on said side plate providing the gateway 28.

Fig. 6 is a detail view of the forward part of the hinged joint between the hinged side plate 11 and its hinge plate 12, as seen from nearly directly below said parts when the hinged plate is swung outwardly almost to horizontal position.

Fig. 7 is a detail sectional view of the parts showing immediately on line 7—7 of Fig. 3, looking rearwardly but omitting any showing of the cable 35 and with the hinged side plate 11 swung outwardly.

Fig. 8 is a similar sectional view of the parts showing immediately on line 8—8 of Fig. 3, looking forwardly but omitting any showing of the cable 35 and with the hinged side plate 11 swung outwardly.

Fig. 9 is a plan view on a reduced scale of the central portion of a ski with a complete ski harness embodying my invention thereon, including a two-ended heel-engaging cable and a conventional take-up device holding the longer end of the cable and with the other or short end of the cable shown as still held by the releasable cable fastener that is a part of my safety ski harness proper, the parts being shown in their shoe-holding position.

Referring to the drawings in a more particular description, it will be seen that to the central portion of the conventional wood ski 7 there is attached the usual center plate 8. On the inner or left side of this ski is located the usual rigid or fixed but adjustable side plate 9, the horizontal flange of which projects inwardly from the lower side of the side plate itself into the space left between the center plate 8 and the ski itself just to the rear of the front end of said central plate 8. On the other or right side of the ski there is provided the right and hinged side plate 11, which at its lower edge is hinged to the hinge plate 12 therefor, as by interlocking curved eye portions on the plate 11, and on the said hinge plate 12, being pierced by a long hinge pin 19. Suitably spaced up from the bottom of the said plates there are provided the inwardly projecting welt-engaging lugs 16 on the plate 9 and 17 on the plate 11 for the purpose of projecting into the space directly over the opposite edges of the strong, thick, rigid welt of the conventional skier's shoe.

In this safety ski harness as in the regular ski harness, the side plates 9 and 11 are arranged to slant inwardly as they extend forwardly and the said side plates are arranged so as to be closely adjusted laterally to the proper distance apart as by the screws 14 projecting down through the central plate 8, and through the flange portion 10 of the plate 9 and through the hinge plate 12 of the hinged plate 11 through arcuate elongated slots 15 provided in said horizontal flange 10, and in said hinge plate 12, so that as the skier pushes his shoe strongly forward along the central plate 8 the said lugs 16 and 17 will cooperate in the usual way to engage the recesses over the edges of the welt of the shoe, and with said edges of the sole of the shoe directly engaging but with a wedging action, the portions of the side plates 9 and 11 below the said lugs 16 and 17.

Directly forward of the horizontal flange 10 of the fixed side plate 9 and forward of the hinge plate 12, the said central plate 8 is offset downwardly so as to provide a forward portion 8' parallel to and resting directly upon the upper surface of the ski 7, and permanently and strongly fastened thereto as by screws 13 extending through suitable holes in said front piece 8' into the ski 7.

The loose link connection between the upper portion of the fixed side plate 9 and its end of the bridge piece 18 may conveniently consist of an apertured ear 20 provided upon this edge of the bridge piece 18, through the aperture of which extends a finger 21 extending upwardly from the upper edge of the fixed side plate 9. When the parts are in operative position the said ear 20 has its forward and rearward portions resting down upon the upper edge of the fixed side plate 9, as best shown in Fig. 1, and slightly to the rear of the rearward part of this ear 20 there is provided another finger 22 upstanding from the upper edge of the fixed side

plate 9, with said finger having its upper end turned forwardly over the adjacent portion of the ear 20 but spaced somewhat therefrom, so that the said bridge piece may swing somewhat upwardly about the straight finger 21 without the said bridge piece becoming detached from the fixed side plate 9.

Near the other or outer end of the bridge piece the bridge piece is provided with a downwardly extending inturned hook 23, which when the parts are in connected and operative position engages the oppositely located upstanding but outwardly slanting portion 24. It will be understood that the said side plates and the said bridge piece and their interconnected portions are so proportioned and arranged that the said hinged side plate 11 has to be temporarily sprung inwardly in order to bring the hook 23 of the bridge piece into engagement with the outer surface of the cooperating slanted part 24 of the hinged side plate 11. It results from this arrangement that when the parts are so connected their internal tension is sufficient to hold the hook in place upon the swinging side plate. When a sufficient force, as hereafter described, is applied to the rear end of the bridge piece 18 the rearward portion of the bridge piece can begin to swing upwardly towards the position shown in Fig. 4 and as this upward swinging motion continues the hook 23 can be moved upwardly from its engaged portion 24 on the movable side plate. Such upward movement of the hook operates with a camming action to spring the hinged side plate 11 inwardly sufficiently to allow the ultimate disengagement of the hook 23 by upward movement thereof, until the bridge piece in the transverse line of this hook comes more or less to the position thereof shown in dotted lines in Fig. 2. Thereupon the said internal tension given to the side plate 11, which tension has been slightly increased by the inward camming action of the hook 23 upon the slanted portion 24 of the side plate 11, results in a sharp springing outward of the said side plate 11, the force necessary to make the final release of the hook 23 from its engaged portion 24 at the same time resulting in a sharp swinging upward of the bridge piece 18, usually to a position much above the dotted line position of the bridge shown in Fig. 2 and usually with the bridge piece swinging forwardly about the straight ear 21 of the other or fixed side plate 9. This upward swinging of the bridge piece 18 and the contemporaneous sharp swinging outwardly of the hinged plate 11 operates in an obvious manner to instantaneously release the shoe from its former confinement within the side plates 9 and 11 and even the confinement of the sole of the shoe below the two inwardly projecting lugs 16 and 17.

The means for thus imparting an upward movement to the rear side of the bridge piece 18 preferably consists of a prolongation from the central portion of the rear edge of the bridge piece 18, which prolongation curves sharply upwardly and somewhat rearwardly, as plainly illustrated in Figs. 1 to 4 of the drawings. This prolongation is conveniently integral with the bridge piece and constitutes an operating arm 25, which preferably is extended laterally in both directions as best shown in Figs. 1 and 2.

When a skier starts to fall forwardly the sole of the shoe is flexed or bent sharply just to the rear of the portions thereof engaged by the inwardly projecting lugs 16 and 17 until the whole

sole of the shoe rearwardly of said lugs comes to a large angle beginning to approach a right angle and the forward portion of the shoe, commonly called its instep portion, strongly braced by the adjacent forward portion of the instep of the skier's foot, comes into direct and strong engagement with the rear curved face of the operating arm 25 of the bridge piece 18. This engagement of the instep of the skier's shoe results ordinarily in a rolling motion being imparted to the said bridge piece, resulting in the parts beginning to approach the position shown in Fig. 4 with the front of the bridge piece still engaging the top of the fixed side plate and the top forward portion of the hinged side plate, while the said hook 23 begins to slide upwardly along the slanting outer surface of the portion 24 of the hinged side plate 11 and exerts an inwardly acting camming action upon said portion 24, which springs the said upper part of the said hinged side plate inwardly enough to effect the ultimate disengagement of the hook 23 into the position shown in Fig. 4. Thereupon as already intimated, the said hinged side plate 11 will spring sharply outwardly on its pivot 19 and the skier's shoe will be entirely released from the ski.

In some situations the upswinging of the skier's shoe when he is starting to make a forward fall may impart essentially a forward pushing motion to the bridge piece 18 and my bridge piece is adapted to be detached also under such forward swinging motion imparted to the bridge piece. Under these circumstances the hook 23 is pushed forward relative to the relatively short slanting portion 24 measured from front to rear of said portion until the hook slides off the front end of said engaged portion 24, which sliding off operates to effect an entire detachment of the bridge piece from the top of the hinged side plate, by reason of a notch 26 provided in the upper edge of the side plate 11 just forwardly of the slanted portion 24, as best appears in Figs. 3 and 4. This notch in combination with the fact that the forward upper corner 27 of this side plate 11 is bent outwardly as best appears in Fig. 1, and also in the detail top view of this side plate shown in Fig. 5, allows quick detachment of the joint on forward movement of the hook 23. As will be obvious from the showing in Fig. 5 the outward bending of this upper front corner 27 of the hinged side plate 11, especially with the upper portion of said portion slanting outwardly as it extends backwardly, provides a gateway 28 through which the hook 23 may pass as it is pushed forwardly on said forward motion of the bridge piece, until the rear end of the hook becomes entirely clear of the front end of the said outwardly slanted portion 24 that has been engaged by the said hook 23. This forward motion of the bridge piece may occur without so much of an inward camming action imparted to the side plate 11 as occurs when the said hook is forced directly upward but there is still sufficient internal tension in the parts to cause the sharp instantaneous outward swinging of the hinged side plate 11 that has already been described in detail as following the upward motion of the said hook, and thereby the shoe of the skier will be instantaneously released from the harness of the ski.

As a precaution against an unwanted and unnecessary detachment of the bridge piece in my device from the hinged side plate, if a skier runs into deep hard snow that might put a great deal of pressure against the front of the operating

arm 25, I provide on the front outer corner of the bridge piece 18 a downwardly extending back-turned hook 29 which normally engages forward of and beneath a forwardly extending projection 30 as best appears in Figs. 3 and 4.

This hook so engaging the projection 30 obviously forms a positive stop against the bridge piece 18 being forced rearwardly along the upper edge of the side plate 11, but it does not interfere with the detachment of the hook 23 from its latching engagement with said side plate 11 either by upward rolling movement of the bridge piece 18 or by forward sliding movement of the bridge piece 18. Upon a disengagement effected by upward movement of the part of the bridge piece carrying the hook 23, this upward swing of the hook 23 is not interfered with until the bridge piece goes even somewhat higher up than indicated in Fig. 4 and by that time the sharp outward swinging action of the whole side plate 11 takes place, which, as will be apparent from Figs. 3 and 4, will carry the projection 30 out from the said hook 29. Similarly on an ordinary forward sliding action of the bridge piece 25 the hook 29 will be withdrawn from beneath the projection 30 by the time the hook 23 has cleared its cooperating part 24 upon the bridge piece.

In many forms of ski harnesses there is provided a strong flexible and somewhat elastic cable, which has its rearward loop passing around the heel of the ski shoe and its forward ends attached to a conventional adjustable take-up device (not shown except in Fig. 9) placed on the ski forward of the shoe. For use with this cable there is usually an inwardly extending groove on the rounded rear portions and sides of the heel of the ski shoe to hold the cable in place. The tension of this ski cable helps to hold the ski shoe wedged forwardly in the harness and so connected to the ski.

As a further precaution against accidents and as a further feature of my safety ski harness I modify the cable so as to have only one end of the loop of cable connected to the adjustable take-up device on the ski forward of the shoe, and I reduce the length of the other end of the cable so that this shortened end comes opposite the forward portion of the hinged side plate 11.

On one eye portion, say the forward eye portion 31 of the hinged side plate 11, I provide an enlargement 32, which as shown in Fig. 1, projects outwardly from the ordinary body of the pin-perforated eye piece 31 when the hinged plate 11, of which this eye piece is preferably an integral part, is in upright position. This enlargement on the eye piece has a socket 33 projecting thereinto from the rear end of the enlargement, which socket is adapted to receive a ball 34 provided and securely attached to the forward end of this shortened end 35 of the cable 36. On the pin-pierced eye piece 37 that is preferably integral with the hinge plate 12 and which eye section is immediately to the rear of the eye section on the hinged plate 11, having the said socket 33, there is provided another enlargement 38. This enlargement 38 projects outwardly practically in line with the hinge plate 12, which carries this eye piece 37 so that when the hinged side plate 11 is in normal operating or upright position as shown in Fig. 1, the socket 33 and the enlargement 32 which bears it are practically in alignment with the enlargement 38, as appears in Fig. 1. The enlargement 38 is cut away on its lower side to allow the rearward passage of the cable 35 from its ball 34 in the socket 33.

In Figs. 1 and 3 the enlargement 32 carrying the socket 33 is shown in horizontal alignment with the enlargement 38, as when the hinged side plate 11 is in upward or operating position. In this position the ball 34 on the forward end of this portion 35 of the cable 36 is in the socket and is locked in the socket by the enlargement 38 immediately to the rear of the socket operating as a cover or cap over the rear end of the socket and so locking the ball within the socket. The so-called "worm's eye" view Fig. 6 of the part of the hinged joint providing the socket 33 and the enlargement 38 shows the enlargement 32 on the forward eye portion of the hinged plate when the hinged plate is swung outwardly, and so the socket 33 is out of alignment with the enlargement 38 on the eye portion 37 of the hinged plate. In this view the ball 34 at the end of the cable 35 is shown as still remaining in the forward socket and with the wires forming the core of the cable projecting rearwardly from said ball, although it will be understood that ordinarily by the time the socket 33 is thus swung outward from the enlargement 38, the ball would normally have been drawn out of the socket, due to the tension ordinarily placed upon the cable portions, both 35 and 36.

This same view from below shows the groove formed in the lower side of the enlargement 38 for the purpose of providing a clearance for the rearwardly extending wires forming the said core of the cable 35 when the ball of said cable is moved up so as to be locked in the socket 33. It will be understood that this groove 39 is only large enough to provide clearance for the wires of the cable and is not large enough to permit the escape of the ball itself from the socket 33. Ordinarily of course the ball will be placed in the socket while the hinged side plate is still swung outwardly and then when the said hinged side plate is swung upwardly and latched in operating position, the said ball will be locked in its said socket. Thereafter the adjustable take-up device will be operated to impart the usual spring tension of the cable to the back of the heel of the ski shoe in the ordinary way. But when the detachable connection between the hinged side plate and the bridge piece is tripped or disengaged by the foot of the skier being raised so that his shoe sharply impinges against the operating arm of the bridge piece, bringing about an instantaneous release and outward swing of the hinged plate, the forward socket 33 will be swung downwardly out of alignment with the enlargement that has heretofore confined the ball in said socket and the tension normally upon the said heel-engaging cable will draw this end of the cable carrying the ball 34 out from the socket and thus even the heel of the shoe will be promptly released from the forward urge thereto imparted to the shoe to stay in engagement with the side plates of the harness. When a loop of elastic cable has been placed about the heel of the skier's shoe and drawn taut thereagainst by a take-up device of conventional form in front of the shoe, pulling that end of the cable forwardly while the second end of the cable is held fast by a releasable fastener near the toe of the shoe (see Fig. 9), it will be obvious that upon the second end of the cable being released from such releasable fastener, the loop of the cable will be released from the heel and in fact will quickly spring away therefrom.

It will thus be seen that I have provided for

an instantaneous release of the heel-engaging cable by the same movement that operates to disengage the hinged side plate from its holding bridge piece, and this has been done without complicating or adding anything to the primary construction and without adding to the difficulty of detachment of the said parts when the forward fall produces a disengagement of the swinging hinged plate from its holding bridge piece.

By thus combining the emergency detachment of the said cable with the emergency detachment of the swingingly mounted hinged side plate, the efficacy of the safety features of this ski harness is in effect doubled in that the shoe is not only released from its engagement between the side plates of the harness, but is also released from the forward urge of the spring-tensioned cable. In this way the ski shoe is substantially 20 instantaneously and completely disengaged from the ski.

The backward pull of the tension on the short cable 35 exerts a considerable downward pull on the outwardly projecting enlargement 32 containing the socket 33, which downward pull on the enlargement is a further aid in swinging the hinged side plate 11 outwardly.

The upwardly and rearwardly bent operating arm 25 can be adjusted to have its upper end 30 and rear side just the proper distance forward of the cooperating instep portion of the shoe of that particular skier so as to get the desired quick and sure tripping of the device. Such adjustment can, in an obvious manner, be made 35 by bending as in a vise the metal of the arm which will thereafter stay at the adjusted position, since it requires relatively little pressure of the skier's shoe on the arm 25 to trip it, and this amount of pressure could not possibly distort 40 the arm 25 or impair its future operation.

What I claim as new and desire to patent is:

1. In a ski harness the combination of a pair of shoe-engaging side plates projecting up from the ski, one plate being rigid relative to the ski, 45 the second plate having its lower edge hinged relative to the ski and adapted to swing outwardly, a bridge piece having an upwardly and rearwardly extending rigid operating arm, said bridge piece having one end loosely connected to the upper part of the fixed side plate and having its other end detachably connected to the upper end of the hinged side plate, said connection placing a tension on said hinged side plate that tends to hold it connected to the bridge piece 50 until positively separated, and that tends to spring said hinged side plate outwardly when the parts are disengaged, said connection of the bridge piece to the hinged side plate being disengaged by upward or forward movement of the 55 bridge piece imparted to the bridge piece through its operating arm by forward pressure thereon from the instep of the shoe when the heel is greatly raised as during a forward fall.

2. In a ski harness the combination of a pair 60 of shoe-engaging side plates projecting up from the ski, one plate being rigid relative to the ski, the second plate having its lower edge hinged relative to the ski and adapted to swing outwardly, a bridge piece having an upwardly and rearwardly extending rigid operating arm, said bridge piece having one end loosely connected to the top of the fixed side plate and having its other end detachably hooked to the upper end of the hinged side plate, said detachable hooked connection placing a tension on said hinged side

plate that tends to hold it connected to the bridge piece until positive separation of said parts and that tends to spring said side plate outwardly when the parts are disengaged, said hooked connection of the bridge piece to the hinged side plate being disengaged by the bridge piece temporarily camming the hinged plate inwardly by upward or forward motion imparted to said bridge piece by pressure from the instep of the upraised shoe.

3. In a ski harness the combination of a pair of shoe-engaging side plates projecting up from the ski, one plate being rigid relative to the ski, the second plate having its lower edge hinged relative to the ski and adapted to swing outwardly, a rigid bridge piece having at its rearward side a centrally disposed rigid operating arm extending rearwardly and then curved upwardly, said bridge piece having its opposite ends reaching to the upper ends of said side plates, the connection to the top of the fixed plate being a loose joint allowing the bridge piece to swing upward thereabouts, the other end of the bridge piece having a downwardly extending inturned hook engaging over an upstanding outwardly slanted portion at the top of the hinged side plate, said parts remaining in holding engagement until forward or upward pressure from the instep of the wearer's shoe upon said operating arm forces the bridge piece upwardly at its rear side, or forces the bridge piece bodily forward, and disengages said hook from the said engaged portion of the hinged side plate, whereupon said bridge piece swings upwardly and said hinged side plate swings outwardly, releasing the shoe from the ski.

4. In a ski harness the combination of a pair of shoe-engaging side plates projecting up from the ski, one plate being rigid relative to the ski, the second plate having its lower edge hinged relative to the ski and adapted to swing outwardly, a rigid bridge piece having at its rearward side a centrally disposed rigid operating arm extending rearwardly and then curved upwardly, said bridge piece having its opposite ends reaching to the upper ends of said side plates, the connection to the top of the fixed plate being a loose joint allowing the bridge piece to swing upward thereabouts, the other end of the bridge piece having a downwardly extending inturned hook engaging over an upstanding outwardly slanted portion at the top of the hinged side plate, said parts through tension thereof when connected remaining in holding engagement until forward or upward pressure from the instep of the wearer's shoe upon said operating arm forces the bridge piece upwardly at its rear side, or forces the bridge piece bodily forward, and disengages said hook from the said engaged portion of the hinged side plate whereupon said bridge piece swings upwardly and said hinged side plate springs outwardly, releasing the shoe from the ski.

5. In a ski harness the combination of a pair of shoe-engaging side plates projecting up from the ski, one plate being rigid relative to the ski, the second plate having its lower edge hinged relative to the ski and adapted to swing outwardly, a rigid bridge piece having one end loosely connected to the upper part of the fixed side plate and having its other end detachably connected to the upper end of the hinged side plate, said connection placing a tension on said hinged side plate that tends to spring said hinged side plate outwardly when the parts are disengaged, 70

said connection of the bridge piece to the hinged side plate being disengaged by upward or forward movement of the bridge piece, and a centrally disposed rigid operating arm extending rearwardly and upwardly from the bridge piece for so moving the same and operated by forward pressure thereon from the instep of the shoe when the heel is excessively raised as during a forward fall.

10 6. In a ski harness the combination of a pair of shoe-engaging side plates projecting up from the ski, one plate being rigid relative to the ski, the second plate having its lower edge hinged relative to the ski and adapted to swing outwardly, a rigid bridge piece having a centrally disposed rigid operating arm extending rearwardly and upwardly and said bridge piece having one end loosely connected to the top of the fixed side plate and having its other end detachably hooked to the upper end of the hinged side plate, said detachable hooked connection placing a tension on said hinged side plate that tends to spring said side plate outwardly when the parts are disengaged, said hooked connection of the bridge piece to the hinged side plate being disengaged by the bridge piece temporarily camming the hinged plate inwardly by upward or forward motion imparted to said bridge piece by pressure from the instep of the shoe upon said operating arm when the shoe is excessively bent as during a forward fall.

7. In a ski harness the combination of a pair of shoe-engaging side plates projecting up from the ski, one plate being rigid relative to the ski, the second plate having its lower edge hinged relative to the ski and adapted to swing outwardly, a bridge piece having one end loosely connected to the upper part of the fixed side plate and having its other end detachably connected to the upper end of the hinged side plate, said connection placing a tension on said hinged side plate that tends to spring said hinged side plate outwardly when the parts are disengaged, said connection of the bridge piece to the hinged side plate being disengaged by upward or forward movement of the bridge piece, and means operatively connected to the bridge piece for so moving the same and operated by forward pressure thereon from the instep of the shoe when the heel is excessively raised as during a forward fall, a tensioned heel cable having one end provided with a ball, a device releasably holding said ball of the heel cable and means releasing said device on the outward swinging of said hinged side plate.

55 8. In a ski harness the combination of a pair of shoe-engaging side plates projecting up from the ski, one plate being rigid relative to the ski, the second plate having its lower edge hinged relative to the ski and adapted to swing outwardly, a bridge piece having one end loosely connected to the upper part of the fixed side plate and having its other end detachably connected to the upper end of the hinged side plate, said connection placing a tension on said hinged side plate that tends to spring said hinged side plate outwardly when the parts are disengaged, said connection of the bridge piece to the hinged side plate being disengaged by upward or forward movement of the bridge piece, and means operatively connected to the bridge piece for so moving the same and operated by forward pressure from the instep of the shoe when the heel is excessively raised as during a forward fall, a tensioned heel cable having one end provided

with a ball, a device releasably holding said ball, said device including an open-ended socket for holding the ball adjacent the hinged joint of said side plate, said socket being closed by an enlargement on an adjacent part of the hinged joint when the said hinged plate is in normal upward position, said socket being opened when the said side plate swings outwardly so that the cable is released simultaneously with the release of said hinged side plate.

9. In a ski harness the combination of a pair of shoe-engaging side plates projecting up from the ski, one plate being rigid relative to the ski, the second plate having its lower edge hinged relative to the ski and adapted to swing outwardly, a rigid bridge piece having at its rearward side a centrally disposed rigid operating arm extending rearwardly and then curved upwardly, said bridge piece having one end loosely connected to the top of the fixed side plate and having its other end detachably hooked to the upper end of the hinged side plate, said detachable hooked connection placing a tension on said hinged side plate that tends to spring said side plate outwardly when the parts are disengaged, said hooked connection of the bridge piece to the hinged side plate being disengaged by the bridge piece temporarily camming the hinged plate inwardly by upward or forward motion imparted to said bridge piece by pressure from the instep of the shoe when the shoe is excessively bent as during a forward fall, a tensioned heel cable having one end provided with a ball, a device releasably holding said ball of the heel cable and means 35 releasing said device on the outward springing of said hinged side plate.

10. In a ski harness the combination of a pair of shoe-engaging side plates projecting up from the ski, one plate being rigid relative to the ski, the second plate having its lower edge hinged relative to the ski and adapted to swing outwardly, a rigid bridge piece having at its rearward side a centrally disposed rigid operating arm extending rearwardly and then curved upwardly, said bridge piece having one end loosely 5 connected to the top of the fixed side plate and having its other end detachably hooked to the upper end of the hinged side plate, said detachable hooked connection placing a tension on said hinged side plate that tends to spring said side plate outwardly when the parts are disengaged, said hooked connection of the bridge piece to the hinged side plate being disengaged by the bridge piece temporarily camming the hinged plate inwardly by upward or forward motion 15 imparted to said bridge piece by pressure on said operating arm from the instep of the shoe when the shoe is excessively bent as during a forward fall, a tensioned heel cable having one end provided with a ball, a device releasably holding said ball, said device including an open-ended socket for holding the ball adjacent the hinged joint of said side plate, said socket being closed by an enlargement on an adjacent part of the hinged joint, when the said hinged plate is in normal upward position, said socket being opened when the said side plate springs upwardly so that the cable is released simultaneously with the release 20 of said hinged side plate.

KARL W. GRUPPE.
